UNITED STATES PATENT OFFICE.

JACOB HUBER, OF BLAKESBURG, IOWA.

CEMENT FENCE-POST.

1,016,151.

Specification of Letters Patent.

Patented Jan. 30, 1912.

Application filed May 29, 1911. Serial No. 630,078.

To all whom it may concern:

Be it known that I, JACOB HUBER, a citizen of the United States, residing at Blakesburg, in the county of Wapello, State of Iowa, have invented certain new and useful Improvements in Cement Fence-Posts; and I do hereby declare the following to be a full, clear, and exact description of the invention, such as will enable others skilled in the art to which it appertains to make and use the same.

This invention relates to fence posts constructed of cement or the like and more especially to an improved reinforcing element and combined attaching means for the fastening staples or nails used in stringing the wires or boards forming the fence.

Another object of the invention is to provide a metallic reinforcing which is formed with a peculiarly formed receiving member or holder for the fastening means of the fence, which will deflect the points of the fasteners to prevent accidental withdrawal thereof but which will permit of their removal for the placing of new fastening devices.

A still further object is to form the holder and reinforcing element of sheet metal in a novel manner, thereby providing a fence post which shall be comparatively simple and durable in use.

With these and other objects in view the invention consists of certain other combinations and arrangements of parts, as will be hereinafter more fully described and claimed, it being a still further object to provide a device which will not be likely to get out of working order.

In the drawings:—Figure 1 is a front elevation of a post constructed in accordance with my invention. Fig. 2 is an enlarged and transverse sectional view thereof on the line 2—2 of Fig. 1, and showing the application of wires by means of staples. Fig. 3 is a similar view but showing boards fastened to the posts by means of nails. Fig. 4 is a detailed perspective view of the reinforcing and fastening element.

Referring to the drawings in detail, there is shown a cement post 10 of any preferred design and contour and which is adapted to be embedded in the ground in the usual manner. In reinforcing the post 10 I employ a strip of sheet metal 11 which is provided with a series of laterally bent cut out tongues 12 so as to firmly adhere to the molded ma-

terial or cement and one vertical edge of the strip 10 is provided with longitudinal incisions 13 which are bent in opposite directions as shown in the sectional views, thereby holding the molded material intact and preventing displacement of the strip in its reinforced position, in the application and withdrawal of the fastening devices now to be described.

In Fig. 2 of the drawings, I have shown the manner of attaching the fence wires 14 by means of staples 15 and in such construction, I provide a sheet metal holder 16 which is bent on itself centrally and vertically as shown at 26 and then rebent as shown at 18 to form a pair of converging channels 19 for receiving the pointed ends of the staples or fastening devices. The sides of the holder 16 are then brought together in divergent relation as shown at 20 and the edges rolled or crimped as shown at 21 and positioned at the face of the post in spaced relation for the entrance of the fastening devices. The reinforcing strip 11 is extended between the convergent sides 22 of the holder and secured upon opposite sides 17 by means of rivets 23, thereby firmly holding the parts together.

In Fig. 3 of the drawings, I have shown the boards 24 secured by nails 25 to the post 10 and it will be seen that the rebent portion 26 will serve to deflect the points of the staples or nails into the convergent channels 19 thereby preventing their accidental withdrawal. It will also be seen that as the channels extend the full length of the post, the fastening devices may be driven at any convenient height and withdrawn as desired without in any manner injuring the post and preventing water from lodging therein by reason of being embedded in the ground.

From the foregoing description it will be readily seen that the reinforcing element and holder may be applied or molded with the cement and may be applied to posts of general design. It will also be seen that the same can be constructed of galvanized iron or other suitable material and when the fastening devices are in position, the oppositely extended flanges 27 formed by the incisions 13 will prevent withdrawal of the holder or dislodgment thereof as would tend to break or crack the cement.

It will thus be seen that the sheet metal reinforcing which may be applied to posts of various characters, is approximately tri-

angular in cross section and when embedded in the post has its sides spaced slightly apart at the apex and exposed through a face of the post at the base thereof so as to form the 5 restricted opening adapted to tightly grip or bind a nail or staple driven thereinto so as to prevent movement thereof vertically and it will be further seen that the side openings formed by the bending of the metal are 10 adapted to similarly grip the fasteners so that the nails or staples will have to be forced therein, thus serving as a further holding means.

I claim:

15 1. A fence post comprising a body, a vertical reinforcing strip embedded in the post, and a holder for fastening devices attached to the strip; said holder comprising a single section of metal bent to form a pair of convergent channels having a restricted receiving portion and rebent edges disposed adjacent to the face of the post.

20 2. A post reinforcing and fence securing element comprising a vertical strip, and a section of metal bent upon itself to form opposite sides between which the said strip is secured, said sides being rebent to form convergent channels having a restricted en-

trance portion, the bent portion of the metal receiving the strip serving to deflect the fastening devices into the channels.

3. A post having fastening receiving means consisting of a sheet of metal bent to form a tube having an approximate triangular cross-section, the tube being embedded 35 in the post and having its sides spaced slightly apart at the apex and exposed through a face of the post, the base of the triangular tube being reentrant.

4. A post having fastening receiving means, consisting of a sheet of metal bent to form a tube having an approximate triangular cross-section, the tube being embedded in the post and having its sides spaced slightly apart at the apex and exposed 45 through a face of the post, the base of the triangular tube being reentrant, and a reinforcing plate secured within the reentrant base.

In testimony whereof, I affix my signature, in presence of two witnesses.

JACOB HUBER.
